MULTIPLE STAGE FLUID RELAY

Donald Preston Eckman, Ithaca, N. Y., assignor,
by mesne assignments, to Minneapolis-Honey-
well Regulator Company, Minneapolis, Minn.,
a corporation of Delaware

Application September 11, 1947, Serial No. 773,397

15 Claims. (Cl. 137—84)

1 The present invention relates to air control apparatus of the widely used type in which a change in the value of a controlling condition adjusts a bleed valve unit to vary a primary control air pressure in accordance with the change in the controlling condition, and in which the change in the primary control air pressure causes a pilot valve unit to produce a corresponding change in a relay control pressure, and in which means are included for producing follow-up and reset actions.

A general object of the present invention is to provide novel air control apparatus of the forced balance type in which the pilot valve adjustments resulting from the changes in the primary control pressure, and the follow up and reset actions are directly effected by mechanical elements which are pneumatic relay or servomotor elements of the Bourdon tube type.

A more specific object of the invention is to provide apparatus of the type specified in which the adjustable elements of the bleed valve unit are rotary elements.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of the invention.

Of the drawings:

Fig. 1 is a diagrammatic perspective view of 35 an embodiment of the invention;

Fig. 2 is an enlarged section through and transverse to the axis of the casing shown in Fig. 1; and

Figs. 3, 4 and 5 are sectional elevations each illustrating a modification of a different portion of the apparatus shown diagrammatically in Fig. 1.

In Fig. 1 I have diagrammatically illustrated an embodiment of the present invention comprising a rotatable indicating or pen shaft 1. The shaft 1 is associated with means for rotating the shaft as required to make its angular adjustment a measure of the value of a controlling quantity which may be some physical condition such as a temperature, rate of flow or head of water, or may be the output pressure of a so-called pneumatic transmitter which maintains an air pressure varying with some variable quantity or condition to which the transmitter is re-

2 sponsive. In the form shown by way of example in Fig. 1, the shaft is angularly adjusted by a Bourdon tube 2 in the form of a spiral and having its inner end connected at 3 to the shaft 1, and having its outer end anchored at 4. The outer end of the spiral 2 is connected to a thermometer bulb 5.

The shaft carries and angularly adjusts a vane or baffle 6 which forms the valve element 10 of a bleed valve unit of which the other element is a bleed nozzle 7.

The baffle 6 is angularly adjustable about the shaft 1, but is normally held against rotation relative to the shaft by a pneumatic adjusting element 8, shown as a Bourdon tube of helical form which surrounds the shaft 1 and has one end 9 attached to said shaft, and which has its other end 10 attached to the baffle 6. The bleed nozzle 7 is shown as parallel to the shaft 1 and is arranged to discharge a jet of air which is obstructed and minimized more or less by the baffle 6 when more or less of the baffle extends into the path of said jet. The plane of the face of the baffle 6 adjacent the nozzle 7 is separated from the end of that nozzle by a very small distance, which may be of the order of two or three thousandths of an inch. Thus, when air under pressure is supplied to the nozzle through a pipe including a restricted orifice, the nozzle pressure 20 may be varied in a definite predetermined manner by a relative angular adjustment of the baffle 6 and nozzle 7 about the axis of the shaft 1. With the edge 6' of the baffle 6 extending into the path of the jet discharged by the nozzle 7, the extent to which the nozzle discharge is throttled by the baffle 6 may be varied significantly by a minute angular adjustment of the baffle in either direction.

The position of the discharge end of the nozzle 7 may be adjusted by means of a control point adjustment member 11. The latter is shown as journaled to turn about the shaft 1. The member 11 may be secured in its different angular adjustments by a clamping screw 12 which extends through an arc shaped slot formed in the member 11 and is threaded into a stationary member 13 against which the slotted portion of the member 11 is clamped. The nozzle 7 is connected to a pipe 14 supplying air under an approximately constant pressure, which may be twenty pounds per square inch. The connection between the nozzle 7 and supply pipe 14 comprises a pipe 15 having one end connected to the pipe 14 and including a restricted portion 55 15', and a flexible pipe 16 connecting the sec-

end end of the pipe 15 to the nozzle 7. The pipe 16 is sufficiently flexible to readily permit the desired control point adjustments of the member 11 and nozzle 7. The path of flow through the restricted portion 15' is made sufficiently small, and the maximum throttling action of the baffle 6 on the nozzle 7 is made sufficiently large to permit a suitably wide range of pressure variation in the nozzle. In practice the range of variation of the nozzle pressure obtainable by the adjustment of the bleed valve unit, may well be from a minimum of about two pounds per square inch to a maximum of about eighteen pounds per square inch, when the supply pressure is twenty pounds per square inch.

The nozzle pressure is transmitted to the helical pneumatic element 8 through a second flexible pipe extension 17 of the pipe 15. The pipe 17 is shown as connected to the element 8 adjacent the end 9 of the latter which is secured to the shaft 1. The purpose and effect of the transmission of the nozzle pressure to the connection 8 between the shaft 1 and the baffle 6, is to produce a follow-up action which, on a change in the temperature of the thermometer bulb 5, prevents the corresponding angular adjustment given to the baffle 6 from being as great as the angular adjustment given to the shaft 1.

Thus, for example, on an increase in the bulb temperature and resultant increase in the fluid pressure transmitted from the bulb 5 to the Bourdon tube 2, the shaft 1 is given a counter-clockwise adjustment, as seen in Fig. 1, which is proportional in extent to the change in the bulb temperature. The angular adjustment of the shaft 1 would produce a corresponding angular adjustment of the baffle 6 if the pressure in the helical tube 8 connecting the shaft 1 and baffle 6 remained constant. However, the decrease in the nozzle pressure produced by the initial movement of the baffle 6 relative to the nozzle 7, is transmitted from the pipe 14 through the pipe 17 to the tubular element 8. The resultant pressure decrease in the helical tube 8 results in partial winding up of that tube, and thus gives the baffle 6 a clockwise adjustment, so that the ultimate counterclockwise adjustment, of the baffle 6 produced by the bulb temperature change is smaller than the ultimate adjustment given the shaft 1 as a result of said change. Conversely, a decrease in the thermometer bulb temperature and pressure produces a corresponding clockwise adjustment of the shaft 1 and a somewhat smaller clockwise adjustment of the baffle 6.

In the form of the invention shown in Fig. 1, the variations in the pressure in the nozzle 7 produces control actions by effecting angular adjustments of a baffle or vane 18 which forms the movable valve element of a pilot valve mechanism. The latter comprises a chambered casing 19 in which the vane 18 is supported and rotated by a valve shaft 20 which extends into the casing 19 through a stuffing box 21 carried by the casing wall. Associated with the baffle 18 is a bleed nozzle 22 and an exhaust nozzle 23, each of which is supported by and extends through the end wall of the casing 19. External to the casing 19, the exhaust nozzle 23 opens to the atmosphere, and the bleed nozzle 22 is connected to the pipe 14 through which air under pressure is supplied to the apparatus.

The vane 18 and nozzles 22 and 23 are so relatively arranged that when the baffle 18 is at one limit of its effective range of angular adjustment, the baffle extends entirely across the path of the

jet discharged by the nozzle 22 and thus exerts a maximum throttling action on said discharge. In this condition of the apparatus, the baffle 18 is out of register with the adjacent end of the exhaust nozzle 23 so that the relatively small amount of air then entering the casing 19 can escape through the exhaust nozzle 23 at the same rate at which it enters through the nozzle 22, without requiring the pressure in the casing to be above more than about two pounds above the pressure of the atmosphere. When the baffle 18 is at the opposite limit of its effective range of oscillation, it has a portion in register with the exhaust port 23 and is entirely out of the direct path of the jet discharged by the nozzle 22, and the pressure in the casing 19 then builds up to about eighteen pounds per square inch.

In intermediate positions of the baffle 18, the latter subjects each of the nozzles 22 and 23 to a throttling action which is smaller than the above mentioned maximum throttling action of that nozzle. In the central position of the baffle shown in Fig. 2, the baffle 18 similarly throttles the two nozzles 22 and 23. The diameters of the bores of the nozzles 22, 23 and 7, and the distance between each nozzle and the plane of the adjacent face of the corresponding baffle valve may be in accord with the usual practices of the air controller art. It is to be noted that in Fig. 2, the diameters of the orifices of the nozzles 22 and 23 adjacent the baffle 18 are exaggerated for illustration purposes. The diameters of the nozzle bores, or at least of the orifices at the ends of the passage adjacent the corresponding baffle portions, are quite small in the case of each of the nozzles 22 and 23, and may be even smaller in the case of the previously mentioned nozzle 7. While the pilot valve pressure range may well be about the same as the range of the pressure in the nozzle 7, the maximum rate of air flow through the pilot valve nozzle 22 will be substantially greater than the maximum rate of air flow through the nozzle 7. The varying control pressure maintained in the casing 19 is transmitted through an outlet pipe 24 from the casing 19 to a control device 25. The latter, as shown diagrammatically in Fig. 1, is a diaphragm control valve. The valve 25 may be employed, for example, to regulate the supply of fuel to a furnace to the temperature of which the bulb 5 responds.

With the particular apparatus shown in Fig. 1, increases and decreases in the pressure in the nozzle 7 produce clockwise and counter-clockwise angular adjustments respectively, of the shaft 20. Those adjustments of the shaft 20 are produced by a pneumatic element 26 in the form of a Bourdon tube extending helically around the shaft 20 and having one end connected to that shaft at the point 27, and having its other end connected by a stationary tube section 28 to the stationary pipe 14. The pneumatic element 26 operates on an increase or decrease in the pressure in the nozzle 7 to produce a clockwise or counter-clockwise adjustment respectively of the valve shaft 20.

The extent of the angular adjustment given the valve shaft 20 in immediate response to a change in the pressure in the nozzle 7, is reduced by the follow-up action of a pneumatic element 29 and is subsequently increased by the reset action of a pneumatic element 32. As shown in Fig. 1, each of the elements 29 and 32 is a helical Bourdon tube surrounding the shaft 20. The pneumatic element 29 has one end 30 connected to the shaft 20, and has its opposite end

31 connected to the pilot valve output pipe 24. The pneumatic element 29, similar to the element 26, is so formed and arranged that increases and decreases in the pressure transmitted from the pipe 24 to said element 29 tend to give the shaft 20 clockwise and counter-clockwise adjustments, respectively. The pneumatic element 32 has one end 33 closed and connected to the shaft 20, and has its other end connected to the outlet pipe 24 through a throttling valve 34. In form and arrangement the element 32 is unlike the elements 26 and 29, in that an increase or decrease in the pressure transmitted to the element 32 from the pipe 24 produces a counter-clockwise or clockwise movement, respectively, of the shaft 20. The valve 34 may be adjusted so that the full effect of a pressure change in the outlet pipe 24 is not transmitted to the pneumatic element 32 except after a delay period which may be a few seconds, or may be a few minutes, depending on the character of the regulation required.

From the foregoing it will be apparent to those skilled in the art that the regulation obtainable with the apparatus shown diagrammatically in Fig. 1 may be similar in type to that obtainable with the usual types of air control apparatus having follow-up and reset provisions now in general use.

In air control apparatus including a bleed valve unit adjusted in accordance with changes in a controlling condition and including a pilot valve adjusted in accordance with variations in the nozzle pressure of said unit, the rotary mode of adjusting the elements which must be adjusted to effect pilot valve adjustments and to effect follow-up and reset actions, is the ideal adjustment mode. The use of helical or spiral Bourdon tube elements in lieu of the bellows or diaphragm elements heretofore customarily used to effect pilot valve adjustments, and to effect follow-up and reset actions, reduces the inherent bulk, weight and construction cost of the apparatus. It also eliminates the necessity for pivoted link and lever elements, and eliminates the friction, wear and risk of lost motion incident to the use of such elements.

To obtain greater overall compactness, the three helical elements 26, 29 and 32 curved about the valve shaft 20 in Fig. 1 may be arranged concentrically, as shown in Fig. 3. The helical elements 26, 29 and 32, shown in Fig. 1 may be replaced by spiral Bourdon tubes 26a, 29a and 32a similar to the spiral tube 2 and curved about the shaft 20 with the inner end of each spiral secured to said shaft, and arranged side by side, as shown in Fig. 4. The present invention may be used with advantage on concentric indicating pneumatic receiver instruments, and on concentric indicating potentiometers. In some cases, the pneumatic helical or spiral elements of an instrument may be mounted on the instrument pen shaft with a corresponding simplification of the control system.

The rotary pilot valve shown in Fig. 1 may take other forms, one of which is illustrated in Fig. 5. In Fig. 5, the pilot valve shown comprises a casing 19a into which the rotary valve shaft 20 and nozzles 22 and 23 extend, as in Figs. 1 and 2. In Fig. 5, however, the single rigid baffle 18 of Fig. 1 is replaced by a flapper valve 36 and a flapper valve 37 pivoted at 38' and 37', respectively. The valves 36 and 37 subject the nozzles 22 and 23 respectively, to inverse throttling effects which variably throttle

the nozzles 22 and 23 as the valve shaft 20 is oscillated. As shown, the flappers 36 and 37 are subject to deflection away from the corresponding nozzles 22 and 23 by projections 38 and 39, respectively, carried by a lever 40 secured to the shaft 20 and each radially displaced from said shaft. As shown, each of the flapper valves 36 and 37 is biased for movement into engagement with the corresponding nozzle by a bias spring 41. As shown, each flapper valve is pivotally connected to and supported by the casing 19.

While in accordance with the provisions of the statutes, I have illustrated and described the best forms of embodiment of my invention now known to me, it will be apparent to those skilled in the art that changes may be made in the forms of the apparatus disclosed without departing from the spirit of my invention as set forth in the appended claims, and that in some cases certain features of my invention may be used to advantage without a corresponding use of other features.

Having now described my invention, what I claim as new and desire to secure by Letters Patent, is:

1. Air control apparatus comprising a bleed valve unit including nozzle and baffle elements relatively adjustable about an axis to effect a change in the bleed valve nozzle pressure on a change in the value of a control quantity, a pilot valve mechanism including an element angularly adjustable about an axis to vary a control pressure, and a Bourdon tube element curved about said axis and through which the last mentioned element is angularly adjusted about said axis in response to changes in the bleed nozzle pressure.

2. Air control apparatus comprising a bleed valve unit including nozzle and baffle elements relatively adjustable about an axis to effect a change in the bleed valve nozzle pressure on a change in the value of a control quantity, and a pilot valve mechanism including an element angularly adjustable about a second axis to vary a control pressure, a Bourdon tube element curved about said second axis and through which the last mentioned element is adjusted in response to changes in the bleed nozzle pressure, and a second Bourdon tube curved about said second axis giving the last mentioned element a follow-up adjustment on a change in said control pressure.

3. Air control apparatus comprising a bleed valve unit including nozzle and baffle elements relatively adjustable about an axis to effect a change in the bleed valve nozzle pressure on a change in the value of a control quantity, and a pilot valve mechanism including an element angularly adjustable about a second axis to vary a control pressure, a Bourdon tube element curved about said second axis and through which the last mentioned element is adjusted in response to changes in the bleed nozzle pressure, a second Bourdon tube curved about said second axis giving the last mentioned element a follow-up adjustment on a change in said control pressure, and a third Bourdon tube curved about said second axis giving the last mentioned element a reset adjustment on a change in said control pressure.

4. Air control apparatus including, a bleed valve unit including nozzle and baffle elements relatively adjustable to effect a change in the bleed valve nozzle pressure on a change in the value of a control variable, a pilot valve mech-

anism including a pilot valve element angularly adjustable about an axis to vary a control pressure, two Bourdon tubes each curved about said axis and having one end secured to said pilot valve element and having its other end stationary, a conduit connecting said nozzle to one of said Bourdon tubes for transmitting the nozzle pressure to actuate the tube and thereby vary the pilot valve outlet pressure, and a conduit connecting said pilot valve to the other of the Bourdon tubes for transmitting the outlet pressure of the pilot valve thereto.

5. Air control apparatus as specified in claim 4, in which said Bourdon tubes are concentric helices.

6. Air control apparatus as specified in claim 4, in which said Bourdon tubes are side-by-side coaxial spirals.

7. A compact air control apparatus including, a shaft mounted for angular movement about its longitudinal axis, a measuring element having a spiral portion coiled about said axis and having a fixed end and a free end connected to said shaft and movable in a curved path in response to the changes in a controlling condition so as to give angular adjustment to said shaft, a nozzle adapted for connection to a source of fluid pressure, a conduit connected to said nozzle, a baffle freely rotatable on said shaft and cooperating with said nozzle to control the flow of fluid therethrough, and an expansible element mechanically connected at one end to said shaft and at the other end to said baffle and having its interior pneumatically connected to said conduit so that the pressure of the fluid flowing through said nozzle gives follow-up adjustment to said baffle.

8. A compact fluid-pressure-operated controller including, a bleed valve including a segment mounted for rotation about an axis perpendicular to the plane of said segment in response to changes in the value of a controlling condition, a bleed nozzle cooperating with said bleed valve so that the flow of fluid through said nozzle is controlled by said bleed valve, a pilot valve including a second segment mounted for rotation about an axis perpendicular to the plane of said second segment, a pilot nozzle adapted for connection to a source of fluid pressure and cooperating with said pilot valve so that the flow of fluid through said pilot nozzle is controlled by said pilot valve, and an expansible spiral having one end fixed and one end attached to said pilot valve and encircling the axis of said pilot valve and connected to said bleed nozzle so that the flow of fluid through said bleed nozzle causes said spiral to rotate said pilot valve.

9. A fluid-operated controller including, a pair of relatively movable bleed valve elements, a pair of relatively movable pilot valve elements, one element of each pair of elements being mounted for angular adjustment about an axis, a measuring element having a spiral portion coiled about the axis of the bleed valve elements and responsive to the changes in value of a controlling condition and having a free end connected to the movable one of said bleed valve elements to move it, a spiral expansible element connected under the fluid control of the other of said bleed valve elements and having mechanical connection with the movable pilot valve element and responsive to the fluid pressure controlled by said bleed valve elements to rotate the movable one of said pilot valve elements.

10. Fluid-pressure-operated control apparatus including, a pair of cooperating relatively mov-

able bleed valve elements, the movable one of said bleed valve elements being rotatable in response to the variations of a controlling condition, a pair of cooperating pilot valve elements relatively rotatable about an axis, a spiral expansible element responsive to the pressure controlled by said bleed valve elements and coiled about said axis and mechanically connected to the movable one of said pilot valve elements to give it a primary rotary adjustment, and a second expansible spiral coiled about said axis and mechanically connected to the movable one of said pilot valve elements to rotate it in the opposite direction to said first spiral in response to changes in pressure controlled by said pilot valve elements.

11. Fluid-pressure-operated control apparatus according to claim 10 having, a third expansible spiral coiled about said axis and mechanically connected to the movable one of said pilot valve elements to rotate it in the same direction as said first spiral, a conduit connecting said third spiral to the pressure controlled by said pilot valve elements, and a restriction in said conduit to delay the flow of pressure therethrough to said third spiral.

12. Air control apparatus comprising a pair of relatively movable bleed valve elements and a pair of relatively movable pilot valve elements one of each pair of elements mounted for angular adjustment about an axis and cooperating collectively to vary a control pressure in accordance with the variations in the value of a control quantity, a spiral expansible element curved about the axis of one of said pairs of valve elements and having a fixed end and a free end fastened to the movable one of one of said pairs of valve elements to rotate it, a conduit for applying to said spiral expansible element air pressure varied by the movements of one of said pairs of valve elements, a second spiral expansible element curved about the axis of the other of said pairs of valve elements and having a fixed end and a free end fastened to the movable one of said other of said pairs of valve elements to rotate it, and a second conduit for applying to said second spiral expansible element air pressure varied by the movements of said other of said pairs of valve elements.

13. Air control apparatus including, a bleed valve unit including nozzle and baffle elements relatively adjustable to effect a change in the bleed valve nozzle pressure on a change in the value of a control variable, a pilot valve mechanism including a pilot valve element angularly adjustable about an axis to vary a control pressure, three Bourdon tubes each curved about said axis and having one end secured to said pilot valve element and having its other end stationary, a conduit connecting said nozzle to one of said Bourdon tubes for transmitting the nozzle pressure to actuate the tube and thereby vary the pilot valve outlet pressure, a conduit connecting said pilot valve to each of the other Bourdon tubes for transmitting the outlet pressure of the pilot valve thereto, and a throttling valve interposed in said conduit between said pilot valve and one of said other Bourdon tubes for causing said Bourdon tubes to actuate said pilot valve element with a reset mode of operation.

14. Air control apparatus as specified in claim 13, in which said Bourdon tubes are concentric helices.

15. Air control apparatus as specified in claim

9

13, in which said Bourdon tubes are side-by-side coaxial spirals.
